* cited by examiner

Primary Examiner — Holly Bayham*Assistant Examiner* — Rhea Shields(74) *Attorney, Agent, or Firm* — Wood, Phillips, Katz, Clark & Mortimer(57) **CLAIM**

The ornamental design for a housing for storage of flexible line, substantially as shown and described.

DESCRIPTION

FIG. 1 is a front, top, and side perspective view thereof;

FIG. 2 is a front elevation view thereof;

FIG. 3 is a rear elevation view thereof;

FIG. 4 is a plan view thereof;

FIG. 5 is a bottom view thereof;

FIG. 6 is an elevation view from the same side as in FIG. 1; and,

FIG. 7 is an elevation view from the side opposite that in FIG. 6.

In the drawings, the broken lines are for the purpose of illustrating environment only and form no part of the claimed design.
